(No Model.)

O. P. ELTERICH.

FIRE PARTING FORK FOR STOVES OR FURNACES.

No. 429,120.

Patented June 3, 1890.

Fig. 1.

UNITED STATES PATENT OFFICE.

OTTO P. ELTERICH, OF NEWARK, NEW JERSEY, ASSIGNOR TO THE ELTERICH ART TILE STOVE WORKS, OF SAME PLACE.

FIRE-PARTING FORK FOR STOVES OR FURNACES.

SPECIFICATION forming part of Letters Patent No. 429,120, dated June 3, 1890.

Application filed July 2, 1889. Serial No. 316,331. (No model.)

To all whom it may concern:

Be it known that I, OTTO PAUL ELTERICH, of Newark, New Jersey, have invented an Improved Fire-Parting Fork for Stoves or Furnaces, of which the following is a specification.

The object of my invention is to permit the ashes and cinders from the lower part of a bed of fire in a stove or furnace to be removed without removing the unburned coals and bright fire above the ashes.

The invention consists in the novel combinations of parts that will be more fully hereinafter set forth.

Reference is to be had to the accompanying drawings, forming part of this specification, wherein—

Figure 1 is a vertical cross-section on the plane of the line *c c*, Fig. 2, showing a portion of a furnace and its fire-pot, my improved fire-parting fork being shown in position for supporting the unburned coals in the fire, while the ashes beneath have been removed. Fig. 2 is a plan view of the fire-pot and the fork in position in the same, and Fig. 3 is a perspective view of my improved fire-parting fork.

In the drawings, the letter *A* represents the casing or frame-work of a suitable stove or furnace, in which is hung a grate *B*. The grate *B* is shown pivoted at or near its ends and adapted to turn on said pivots, as indicated by dotted lines, so as to deposit the ashes, &c., from the same upon the receptacle *b* beneath it; but the grate *B* may be a sliding grate or of any other desired construction, whereby the ashes it supports may be deposited in a receptacle.

D is a fire-pot above the grate *B*, and is shown provided with a series of slots or apertures *d*. The lower end of the fire-pot *D* comes near the grate *B*, so that the ashes will be suitably supported within the same in the usual manner. The fire-pot *D* may be of any desired construction, provided it has suitable openings *d* to permit the passage of my improved fork *E* across the fire-pot, as clearly indicated in Figs. 1 and 2. The fork *E* consists of a head *e*, from which project a number of prongs *f*. (See Fig. 3.) On the side of the head *e* opposite the prongs *f* are sockets

g, that are adapted to receive lugs *h*, carried by a handle *F*, whereby the fork may be manipulated. By this construction the handle *F* may be removed from the fork when the fork is passed into the fire-pot *D*.

As shown in Fig. 1, the casing *A* of the furnace is provided with a horizontal tube-like opening *G*, formed by two shelves or supports *i, j*, into and through which opening the fork *E* may be passed. The opening *G* is aligned with openings *d* in the fire-pot *D*, and the fork *E* rests upon the lower shelf *i*, as indicated. The distance between the shelves *i, j*, or, in other words, the height of the opening *G*, is about the same as or slightly more than the height of the head *e* of the fork *E*, so that said head will have a free sliding movement within said opening, and so that the upper side of the head *e* will come against the shelf *j*, while the under side of the prongs *f* and head *e* rest upon the shelf *i*, thereby preventing the outer ends of the prongs *f* being depressed by the weight of the coals, the fork being entirely supported by the head *e* in the opening *G*. The head *e* closes the opening *G* to prevent the passage of dust. The sockets *g* are so arranged on the head *e* as to permit the lugs *h* to be withdrawn from the same by a downward and outward movement when the fork is in the opening *G*, as indicated in Fig. 1.

l is the door of the furnace, which may be of suitable construction and provided with an opening *m* to permit a key or the like to be inserted to operate the grate *B*. The door *l* may also be provided with an opening *n*, that may be covered by a hinged latch or flap *o*, so that the fork *E* may be passed into the furnace and through said opening without opening the door *l*, and so that the handle *F* may be removed from the fork and the opening *n* closed to prevent dust, &c., passing out through said opening.

In using my improved fork I proceed as follows: I pass the fork *E* into the furnace or stove through the opening *G*, so that its prongs *f* will pass through the openings *d* in the fire-pot *D*, and also pass through the bed of coals or ashes in the fire-pot, so as to separate the contents of the fire-pot into two parts. I next remove the handle *F* and close the flap *o*, whereupon I turn the grate *B* upon its pivots,

or otherwise remove the grate from beneath the cinders and ashes, whereupon said cinders and ashes will be deposited upon the receptacle *b* or elsewhere, while the fork *E* sustains the coals and fire above the fork, an open space being left beneath the fork, as clearly shown in Fig. 1. The grate *B* is now returned to its proper position and the fork withdrawn from the fire-pot, whereupon the coals, fire, &c., will pass down upon the grate and continue to burn with new vigor, like a fresh fire, free from cinders and ashes. The door *l* need not extend up as far as the opening *G*, in which case the flap *o* will be attached directly to the casing *A*.

Having now described my invention, what I claim is—

1. The combination of a stove-casing having a fire-pot provided with side openings and a horizontal tube-like opening *G*, with

a fork adapted to pass through said opening *G*, and having a head that fits within said opening and which is supported thereby, so as to hold up the prongs of the fork when they pass through the fire-pot to support the coals, &c., in the same above the grate, substantially as described. 25

2. The fire-fork *E*, consisting of the head *e*, having the prongs *f*, in combination with the supports *i j*, forming a tube-like opening 30 within which the head *e* fits closely, whereby said fork will be held horizontal, while permitting a sliding movement, the outer ends of the prongs being unsupported, substantially as described.

OTTO P. ELTERICH.
